UNITED STATES PATENT OFFICE.

H. F. BRYANT, OF MARATHON, NEW YORK.

DENTAL DRILL.

Specification forming part of Letters Patent No. 71,361, dated November 26, 1867.

To all whom it may concern:

Be it known that I, H. F. BRYANT, of Marathon, in the county of Cortland and State of New York, have invented a new and useful Improvement in Drill for Teeth; and I do hereby declare that the following is a full, clear, and exact description thereof, which will enable others skilled in the art to make and use the same, reference being had to the accompanying drawings, forming part of this specification, in which—

Figure 1 is a central longitudinal section of my improved teeth-drill. Fig. 2 is a cross-section in the line xx , Fig. 1, showing the drill attachment.

Similar letters of reference indicate like parts.

The design of this invention is to supply a desideratum always existing in the profession of dentistry, and never hitherto provided for, by the construction of an instrument by which the posterior and table surfaces of the molar teeth can be drilled, and excavated for cleaning and filling, with equal facility to the anterior or any other parts of any of the teeth.

A burnished steel or iron tube, A, closed at the end, is attached to a neat handle, B. In the tube A is fitted nicely a sliding rod or piston, a, which extends back into the handle B, where the end bears upon a spiral spring, b, which by its expansion forces the piston a to the extreme end of the tube A. On the outer end of the piston is a rack, c, the teeth of which engage in a pinion, d, that is hung in a side box, e, on a hollow shaft, as shown in Fig. 1.

A ring, f, is attached to the piston a and moves in a slot in the side of the tube A, for the purpose of sliding the piston back and forth, and giving motion to the pinion d. A delicate drill, g, for boring cavities in the molar teeth, is fitted on either side in the hollow shaft of the pinion d, as shown in Fig. 2.

The operation of drilling with this instrument is performed by holding the drill in position on the tooth with one hand, and drawing the piston by the ring with a finger on the same hand, which gives motion to the pinion in one direction, while by the relaxation of the pressure of the finger on the ring, the spring, by its expansion, throws the piston in the opposite direction, and reverses the motion of the piston with the drill. By this reciprocating movement of the piston the operation of drilling a molar tooth is nicely and easily performed.

Having thus described my invention, I claim as new and desire to secure by Letters Patent—

The construction and arrangement of the slotted tube A, having side box e, piston a, with the rack c, operating the pinion d, sliding ring f, and hollow handle h, containing the spiral spring, as herein set forth, for the purpose specified.

H. F. BRYANT.
